[57] ABSTRACT

In the particular embodiments disclosed, apparatus for guiding two yarns over a curved surface is combined with a yarn drawing machine including feed rollers, take-up rollers and an intermediate cylindrical stretching element, thereby permitting two yarns to be drawn at the same drawing station. One or a pair of guide arms, each having a guide opening for a yarn at either end, are arranged relative to the cylindrical element to pass the yarns over the element in two spaced planes. The arms and the cylindrical element are pivotable one relative to the other to shift, e.g., interchange, the loci of the yarns on the element. In one embodiment, the guide arms are pivoted while the cylindrical element is held stationary, and in another the cylindrical element is pivoted while the arms remain fixed. Where a pair of guide arms are used, they may be placed on opposite sides of the cylindrical element to guide the yarns in their approach to and departure from the cylindrical element.

YARN GUIDING APPARATUS

BACKGROUND OF THE INVENTION

The present invention relates generally to apparatus for passing two yarns over an element having a curved surface and, more particularly, to guiding apparatus for drawing synthetic yarns.

Although the invention is illustrated and described herein by reference to a machine for drawing synthetic yarn, and specifically one including a cylindrical drawing element, it goes without saying that the invention is in no way limited to this embodiment or use, but that it also has application to all devices formed by at least one curved element over which it is desired to pass two yarns in parallel, whether or not the yarns are to be subjected to a particular treatment.

It is known that in order to give a synthetic yarn its mechanical characteristics, it must be subjected, in succession, after spinning and extrusion, to a stretching or "drawing" operation which has the effect of orienting the molecules of which the yarn is composed. This operation is generally carried out between two devices which draw the yarn, the difference in speed of which is adjusted as a function of the extent to which it is desired to stretch the yarn. In practice, especially with polyamide yarns, between these two drawing devices, the yarn engages most frequently on a fixed rod, which may or may not be heated, sometimes called the "stretching finger," around which it makes one or more turns.

It is also known to insert, between the drawing devices, a heating element of suitable shape over which the moving yarn passes. Finally, one of the drawing devices can be a rotating heating cylinder of the multi-turn type, equipped with a return roller, the yarn making one or more turns around the combination of heating cylinder and return roller.

In order to increase the profitability of stretching machines, it has been proposed to treat several yarns simultaneously at the same stretching station. However, if, during the operation, one of the yarns breaks, this method has numerous disadvantages which make it inapplicable in industry.

If, for example, the yarn which breaks is the one situated at the front or outside location, that is to say that which passes in the plane situated nearest to the free end of the cylinder, it is sufficient to restart this yarn, taking care obviously to avoid it affecting the passage of the other yarn. On the other hand, if it is the yarn situated at the back or inside which breaks, difficulties are encountered: firstly, this broken yarn presents the risk of becoming entangled with its neighbours and thus of causing the whole lot to break; and secondly, and most importantly, it is necessary to stop the whole unit in order to proceed with repairs and a new start. These and other disadvantages of the prior art are overcome by the present invention.

SUMMARY OF THE INVENTION

Generally, the present invention relates to apparatus for passing two yarns over one and the same curved, e.g., cylindrical, element, which may or may not rotate, in which, in the case of breakage of one of the two yarns, it is not necessary to stop the unit to remove and restart the yarn which broke.

A representative embodiment constructed in accordance with the invention includes a cylindrical component over which two yarns pass in two parallel planes, which planes are substantially perpendicular to the axis of the cylindrical component, and at least one guide arm carrying at both of its ends a means of guiding each of the two yarns. The guide arm is positioned in such a way that the two parallel planes of the cylinder in which the yarns pass, i.e., the planes generally containing the yarns as they pass over the cylinder, are spaced apart relative to one another along the axis of the cylinder, and such that each yarn is presented tangentially on either side of the cylinder. The device is characterized further in that the cylindrical component and the guide arm can pivot relative to one another about the same axis to shift the loci of the yarns on the cylindrical component.

In practice, the guide arm and the cylindrical component preferably pivot about an axis formed by the intersection of the plane in which the yarns lie as they approach the cylindrical component with the plane which passes through the axis of the cylinder in a direction parallel to the direction of forward movement of the yarns.

In one embodiment, the invention includes two pivotally mounted guide arms which are parallel and located on either side of the cylinder, preferably symmetrically. In this way, each yarn is guided before and after its passage over the cylinder, which makes it easier to position the yarn. Significant advantages over the prior art are also realized, however, if only one guide arm is employed.

In a first advantageous embodiment, it is the guide arm or arms carrying the yarn guides at their ends which pivot. As already stated, the cylindrical element can be a cylinder forming the engagement component of a machine for drawing synthetic yarns, and may be either fixed or rotatable and heated or unheated. In this way, it is possible to use a single stretching finger for two yarns.

If, during operation, one of the yarns breaks and if this yarn is the one which passes on the inside or back, it is sufficient to pivot the guide arms to the other extreme position and thus to shift the yarn at the front into the position at the back, and then to carry out the restarting of the broken yarn which is now in the position at the front. If subsequently the yarn situated on the inside breaks again, the same procedure is repeated. Thus, since the position of each of the two yarns on the cylinder can be varied alternately and instantaneously from the position at the front to the position at the back, without having to stop the machine, a troublesome problem of the prior art has been solved in a simple, effective and economical way. This makes it possible considerably to improve the yield of drawing machines and enables conventional drawing machines to be readily and inexpensively modified in accordance with the invention.

In a second embodiment, the guide arm or arms are fixed and the cylinder pivots about the axis formed by the intersection of the plane in which the yarns pass with the plane passing through the axis of the cylinder in a direction parallel to the direction of forward movement of the yarns. This embodiment makes it possible to keep the yarns in a fixed position relative to the delivering elements and thus to have constant engagements on the yarns.

BRIEF DESCRIPTION OF THE DRAWINGS

The invention and the advantages which result from it will be better understood from the following description, with reference to the attached figures, in which:

FIG. 1 represents a perspective view of an embodiment of the invention, with pivoting arms;

FIG. 2 is a horizontal view of the embodiment of FIG. 1, taken along the line 2—2;

FIG. 3 is a perspective view of a second embodiment according to the invention, with a pivoting cylinder; and

FIGS. 4A and 4B are partial horizontal views taken along the line 4—4 of FIG. 3, with parts omitted for clarity.

DESCRIPTION OF EXEMPLARY EMBODIMENTS

In the embodiment illustrated in FIG. 1, a cylinder 10, which may be fixed or may be able to rotate and which may or may not be heated, is mounted, by means of a shaft 12, on a generally U-shaped member 14. The member 14 is supported in the axis of the cylinder 10 by a cross bar 16 of a frame (not shown) of a conventional machine for drawing synthetic yarns. The arms 18 and 20 of the U-shaped member 14 are situated in a vertical plane passing through the axis of the cylinder 10 and are respectively placed so that one 18 is above the cylinder and the other 20 below. Close to their free ends, the arms 18 and 20 carry two pivoting pins 22 and 24 which are aligned in the same vertical plane.

Another generally U-shaped member 26 is positioned outside the U-shaped member 14, relative to the cylinder, and possesses two arms 28 and 30. The arms 28 and 30 are pivotally mounted on the pins 22 and 24, respectively. In this way, the outer U-shaped member 26 can pivot relative to the inner U-shaped member 14, which is rigidly fixed to the cross bar 16 of the frame. The upper arm 28 of member 26 is firmly fixed to a double yarn guide arm 32. The lower arm 30 is similarly fixed to another double yarn guide arm 34 which is identical to the first. In the case of the guide arm 32, the yarns 36 and 38 pass through two open eyelet-holes 40 and 42, of suitable shape and nature, situated at the respective ends of the arm 32. Likewise, in the case of the guide arm 34, the yarns pass through two open eyelet-holes 44 and 46. Preferably, the guide arms 32 and 34 are so arranged that the eyelet-holes 40 and 44, on the one hand, and the eyelet-holes 42 and 46, on the other, are vertically above one another.

As a result of the pins 22 and 24 being aligned vertically, the inlet eyelet-hole 40, 42 and outlet eyelet-hole 44, 46 for each yarn 36, 38 also remain vertically aligned throughout in relation to the cylinder 10 whenever the outer U-shaped member 26 pivots and conjointly moves the yarn guide arms 32 and 34.

In the two directions of pivoting which can be applied to the U-shaped member 26, the member comes to rest against the cross bar 16, thus defining two stable positions which are symmetric relative to the axis of the cylinder 10. In one of these stable positions of the member 26 (shown in full lines in FIG. 2), the eyelet-holes 40 and 44 define the passage at the front for one yarn 36, whilst the eyelet-holes 42 and 46 define the passage at the back for the other yarn 38, as seen by an operator

looking straight at the cylinder 10 from the left hand side of FIG. 1.

In the other stable resting position of the U-shaped member 26 (shown in phantom in FIG. 2), the yarn 36 which passes through the eyelet-holes 40 and 44 assumes a path at the back and the yarn 38 of eyelet-holes 42 and 46 assumes a path at the front.

In order to hold the U-shaped member 26 in one or the other of its two resting positions, the upper arm 28 carries a pivot pin 48 which is pivotally engaged by collar 50 attached to one end of a rod 52. The opposite end of the rod 52 passes through an opening in a bar 54 which is firmly fixed to the frame (not shown) of the machine. A compression spring 56 is positioned over the rod 52 and bears against the collar 50 at one end and a detent 58 at the other. The detent is suitably apertured to slidably receive the rod 52 and, on the side thereof facing the bar 54, is formed with a generally spherically-shaped bearing surface. (See FIG. 2) The opening in bar 54 through which the rod 52 passes is correspondingly shaped to provide a spherical seat for the detent 58.

It will be appreciated that, once moved to one of its rest positions, the U-shaped member 26 will be retained in that position by the force of the spring 56. Thus by shifting the U-shaped member 26 either to the right or to the left (as viewed in FIG. 1), using for this purpose the forwardly extending part of arm 28, the operator can, at will, reverse, i.e., shift from the front to the back and vice versa, the paths of the yarns 36 and 38 on the cylinder 10.

When the machine illustrated in FIGS. 1 and 2 is started up, the yarn 38 drawn by the drawing unit, or feed rollers, 60 is inserted into the eyelet-hole 42 situated at the back. The operator causes it to make one or more turns on the cylinder 10 in the clockwise direction, and then inserts the yarn at the outlet into the eyelet-hole 46 which is directly below the hole 42. The yarn 38 is then drawn by the drawing unit, or take-up rollers, 62, the controlled speed of which is greater than that of the unit 60 and in a ratio such as to cause the desired stretching or drawing of the yarn. Likewise, the yarn 36 drawn by the drawing unit, or feed rollers, 64 is passed through the eyelet-hole 40 situated at the front. The operator causes it to make one or more turns on the cylinder 10 in the anti-clockwise direction and inserts the yarn at the outlet into the eyelet-hole 44 which is directly below eyelet-hole 40. The yarn 36 is then drawn by the unit, or takeup rollers, 66, the controlled speed of which is also greater than that of the unit 64 to cause stretching of the yarn.

Preferably, the upper feed units 60 and 64 are driven at the same speed, and the take-up units 62 and 66 are driven at the same faster speed, so as to stretch the two yarns in the same ratio.

If the yarn 38 placed at the back of the cylinder 10, relative to the yarn 36, breaks, the operator pivots the U-shaped member 26. The turn or turns of the yarn 36 placed at the front of the cylinder 10 slide towards the back and take up the position which those of the yarn 38 occupied before the breakage. The eyelet-holes 42 and 46 come to the front during pivoting of the member 26 and it suffices to restart the yarn 38 as explained above. The turn or turns of the yarn 38 then take up the position on the cylinder 10 which the turn or turns of the yarn 36 occupied previously.

FIGS. 3, 4A and 4B illustrate another embodiment of the invention, this time with a pivoting cylinder. Like components are indicated by like primed numbers and, except as otherwise noted, will be understood to function in the same manner as in the embodiment of FIGS. 1 and 2.

Here, the guide arms 32' and 34', carrying at their ends the eyelet-holes 40'-46' for guiding the yarns 36' and 38', are fixed, i.e., the U-shaped member 26' is rigidly attached to the cross bar 16', and the cylinder 10' is arranged to pivot about the axis formed by the intersection of the plane in which the yarns 36' and 38' lie and the plane which passes through the axis of the cylinder 10' parallel to the direction of forward movement of the yarns.

As one suitable arrangement for pivoting the cylinder 10', the inner U-shaped member 14' is pivotally supported within the outer U-shaped member 26' by means of the pins 22' and 24'. It is moved between its rest positions (illustrated respectively in full lines in FIGS. 4A and 4B) in order to bring the eyelet-holes 40' and 44' and yarn 36', on the one hand (FIG. 4A), or eyelet-holes 42' and 46' and yarn 38', on the other (FIG. 4B), to the front. If desired, one of the arms 18' and 20' of the U-shaped member 14' may be extended in the forward direction to facilitate pivoting of the member 14', and hence of the cylinder 10', by the operator.

Conveniently, the cylinder 10' may be positioned at its rest positions by stops 68 and 70 (FIG. 3) carried by the cross bar 16'. The rod 52' may thus extend through an opening in the U-shaped member 26', which serves as a seat for the spherically-shaped detent 58'. As before, a compression spring 56' is constrained between the detent 58' and a collar 50' fixed to the opposite end of the rod 52'. The collar 50' may be pivotally secured to the upper arm 18' of the U-shaped member 14' by a pivot pin 48', so that the spring 58' urges the member 14' against the stops 68 and 70 to hold the cylinder 10' in the proper rest positions.

The yarns 36' and 38' are drawn by the drawing units 60'-66' and passed through the eyelet-holes 40'-46' and around the cylinder 10' in the same manner as in the embodiment of FIGS. 1 and 2. They are likewise restarted if broken in the same manner as previously explained, except, of course, that the cylinder 10' rather than the outer U-shaped member 26' is pivoted to move the broken back yarn to the front position.

In a practical procedure, and whatever the embodiment envisaged, the yarn guides situated at the end of the guide arms preferably are driven in conventional fashion with a slight secondary reciprocating movement in a substantially perpendicular plane relative to the direction of forward movement of the yarns. This is done in order to avoid wear of the cylinder in one spot and to minimize abrasion of the yarns.

As already stated, apparatus constructed according to the invention is particularly advantageous for stretching synthetic yarns because, without excessive alteration of existing material and by means of an apparatus which is simple to construct and easy to use, it is possible to treat two yarns simultaneously at a single drawing station and thus considerably to decrease the investment in future installations and to increase the profitability of those already in existence.

It goes without saying that this device can be used for other purposes than stretching synthetic yarns without

going outside the scope of the present invention. For example, it can be used successfully with any type of treatment which is applied to yarns of any nature, and in which one or two yarns are passed over at least one curved surface which may or may not be rotated and which may or may not be heated. All such modifications and variations of the invention, and of the particular embodiments described above, are therefor encompassed within the spirit and scope of the appended claims.

I claim:

1. Apparatus for simultaneously drawing two yarns comprising means forming a curved surface over which the yarns are to be passed, feed rollers for feeding the yarns to the curved surface, take-up rollers for taking up the yarns after their passage over the curved surface, the take-up rollers being driven faster than the feed rollers so as to draw the yarns by a desired amount, each of the yarns engaging the curved surface and being disposed substantially in a plane, the two planes containing the yarns being spaced apart from each other, means for guiding the first yarn, means for guiding the second yarn, and means for shifting the relative positions of the curved surface-forming means and the first and second guide means so as to shift the loci of the first and second yarns on the curved surface.

2. Apparatus according to claim 1 in which each of the first and second guide means includes a pair of spaced yarn guiding elements, the paired guide elements being disposed on opposite sides of the curved surface forming means.

3. Apparatus according to claim 1 in which the shifting means simultaneously shifts the relative positions of the curved surface forming means and the first and second guide means so as to reverse the loci of the first and second yarns on the curved surface.

4. Apparatus according to claim 3 in which the curved surface is a cylindrical surface, the curved surface forming means is cylinder means, and the two planes containing the two yarns are substantially perpendicular to the axis of the cylinder means.

5. Apparatus according to claim 4 in which the cylinder means is mounted to prevent pivoting about an axis perpendicular to the axis of the cylinder means, and the shifting means shifts the first and second guide means in generally opposite directions.

6. Apparatus according to claim 5 in which the first and second guide means are disposed at least in part at opposite ends of an arm pivoted for rotation about an axis substantially perpendicular to the axis of the cylinder means.

7. Apparatus according to claim 6 in which the first and second guide means are further disposed at opposite ends of a second arm pivoted for rotation about the same axis of the first arm, and the first and second arms are disposed on opposite sides of the cylinder means.

8. Apparatus according to claim 7 in which the shifting means comprises a generally U-shaped member disposed with the arms thereof on opposite sides of the cylinder means and pivoted for rotation about the same axis as the first and second guide means-carrying arms, the first and second guide means-carrying arms being mounted on the respective arms of the U-shaped member for rotation therewith.

9. Apparatus according to claim 8 in which the shifting means further comprises means for releasably holding the U-shaped member, and thus the guide means-carrying arms, in two rotational positions relative to the cylinder means, each rotational position corresponding to particular loci of the first and second yarns on the cylinder means, whereby upon pivoting of the U-shaped member from one rotational position to the other the loci of the first and second yarns on the cylinder means are reversed.

10. Apparatus according to claim 9 in which the shifting means further comprises a second generally U-shaped member disposed within the first U-shaped member, means carried by the second U-shaped member for supporting the cylinder means between the arms thereof, means supporting the second U-shaped member so as to prevent pivoting thereof about an axis perpendicular to the axis of the cylinder means, and means carried by the arms of the second U-shaped member for pivotally supporting thereon the first U-shaped member.

11. Apparatus according to claim 10 further comprising first and second feed rollers for feeding the first and second yarns to the cylinder means and first and second take-up rollers for taking up the first and second yarns after their passage over the cylinder means.

12. Apparatus according to claim 4 in which the first and second guide means are mounted to prevent pivoting about an axis perpendicular to the axis of the cylinder means, and the shifting means shifts the cylinder means in generally opposite directions.

13. Apparatus according to claim 12 in which the first and second guide means are disposed at least in part at opposite ends of an arm fixed against rotation about an axis substantially perpendicular to the axis of the cylinder means.

14. Apparatus according to claim 13 in which the first and second guide means are further disposed at

opposite ends of a second arm fixed against rotation about an axis substantially perpendicular to the axis of the cylinder means, and the first and second arms are disposed on opposite sides of the cylinder means.

15. Apparatus according to claim 14 in which the shifting means comprises a generally U-shaped member disposed with the arms thereof on opposite sides of the cylinder means and pivoted for rotation about an axis substantially perpendicular to the axis of the cylinder means, and means carried by the U-shaped member for supporting the cylinder means for rotation therewith.

16. Apparatus according to claim 15 in which the shifting means further comprises means for releasably holding the U-shaped member, and thus the cylinder means, in two rotational positions relative to the guide means-carrying arms, each rotational position corresponding to particular loci of the first and second yarns on the cylinder means, whereby upon pivoting of the U-shaped member from one rotational position to the other the loci of the first and second yarns on the cylinder means are reversed.

17. Apparatus according to claim 16 in which the shifting means further comprises a second generally U-shaped member disposed around the first U-shaped member, the arms of the second U-shaped member carrying the first and second guide means-carrying arms, means supporting the second U-shaped member so as to prevent pivoting thereof about an axis perpendicular to the axis of the cylinder means, and means carried by the arms of the second U-shaped member for pivotally supporting thereon the first U-shaped member.

18. Apparatus according to claim 1 in which the curved surface-forming means is heated.

19. Apparatus according to claim 1 in which the curved surface-forming means is mounted for rotation about an axis substantially perpendicular to the planes containing the two yarns.
